UNITED STATES PATENT OFFICE.

LEWIS L. SCOTT, OF ST. LOUIS, MISSOURI.

DESIGN FOR A FRONT FOR AN AUTOMOBILE-LAMP.

54,226.

Specification for Design.

Patented Nov. 18, 1919.

Application filed June 5, 1919. Serial No. 302,073. Term of patent 14 years.

To all whom it may concern:

Be it known that I, LEWIS L. SCOTT, a citizen of the United States, residing at the city of St. Louis and State of Missouri, have invented a new, original, and ornamental Design for a Front for Automobile-Lamps, of which the following is a specification,

reference being had to the accompanying drawing, forming part thereof.

I claim:

The ornamental design for a front for an automobile lamp, as shown.

LEWIS L. SCOTT.
